CLAIM

The ornamental design for a “monitor for computer,” as shown and described.

DESCRIPTION

FIG. 1 is a top, front and right side perspective view of a monitor for computer according to my design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side being a mirror image thereof; and,

FIG. 7 is a top rear and left side perspective view thereof.
